WATCH MOUNTING LINK FOR A WATCH BRACELET

Jeffrey Hassman, New York, N.Y., assignor to Jacoby-Bender, Inc., Woodside, N.Y.

Filed June 23, 1971, Ser. No. 156,170

Term of patent 14 years

Int. Cl. D11—01
U.S. Cl. D45—4 B

FIG. 1

FIG. 2

FIG. 3

FIG. 4

FIG. 5

FIG. 1 is a top plan view of a watch mounting link for a watch bracelet showing my new design;

FIG. 2 is a side view thereof;

FIG. 3 is a view of the opposite side;

FIG. 4 is an end view as seen from the left of FIG. 2; and

FIG. 5 is an end view as seen from the right of FIG. 1.

I claim:

The ornamental design for a watch mounting link for a watch bracelet, substantially as shown.
